ZERO FOILS FOR CALCULATING MACHINE

John L. Moody, Oakland, Calif., assignor to Friden, Inc., a corporation of California

Application May 31, 1955, Serial No. 512,100

6 Claims. (Cl. 235—1)

This invention relates to check dials for a calculating machine such as the well known Friden Calculating Machine, and more particularly, to automatically operating zero foils, or covers, for such check dials.

It is among the objects of the invention to provide automatically operating zero foils, or covers, for calculating machine check dials, such as are shown in Patent No. 2,279,456, granted April 14, 1942, to C. M. F. Friden et al., which foils or covers are selectively operated to cover and uncover the window openings, or apertures, in the machine cover through which the check dials are viewed. In its preferred form, the zero foils are controllable by a decimal indicator manually movable from order to order of the check dials to uncover all of the window openings to the right of the decimal indicator while leaving those window openings to the left of the decimal indicator closed. Preferably, also, these foils, or covers, are independently operable in each order of the check dials to uncover the corresponding window openings if the coordinal check dials are turned away from their "0" positions. Finally the foils of the present invention are designed to be applied to an existing calculating machine with no material modification of the machine construction and in a manner not to interfere in any way with the operation of the associated machine.

Other objects and advantages will become apparent from a consideration of the following description and the appended claims in conjunction with the accompanying drawings wherein:

Fig. 1 is a fragmentary, longitudinal cross-sectional view through the rear portion of a conventional "Friden" calculating machine, showing check dials and zero foils for the check dials;

Fig. 2 is a fragmentary cross-sectional view on enlarged scale substantially on the section plane of Fig. 1, as indicated by the lines 2—2 on Fig. 4, showing the check dials and the zero foils therefor;

Fig. 3 is a fragmentary cross-sectional view on the horizontal plane indicated by the line 3—3 of Fig. 2;

Fig. 4 is a fragmentary cross-sectional view, on an enlarged scale, of a front view of the present invention, such as along the transverse vertical planes indicated by the lines 4—4 of Fig. 1;

Fig. 5 is a fragmentary plan view of the mechanism shown in Figs. 1 to 4, such as taken along the horizontal plane indicated by the line 5—5 of Fig. 4; and

Fig. 6 is a perspective view of the foil elements shown particularly in Figs. 3, 4 and 5.

With continued reference to the drawings, the numeral 10 generally designates the frame of the calculating machine, which frame, in addition to other components not illustrated, includes transverse frame members 11, 12, 13, 14 and 15, disposed in spaced and parallel relationship to each other and substantially perpendicular to the base, not illustrated, of the machine, and side plates, of which the left-hand side plate is shown and designated at 16. A register, or accumulator, carriage, generally indicated at 20, is mounted for transverse sliding, or shifting, move-

2

ments on the fixed frame, including the components 11 to 16. The carriage comprises a tubular carriage frame 21 of generally rectangular shape, the rear side of which is slidably mounted on a rail 22 mounted on the inner side of the rear transverse frame member 15 near the upper edge of this frame member and the front end of which is mounted on rollers 25 and carried by an upper transverse member 26 of the fixed frame.

A transverse main, or power, shaft 30 extends across 10 the machine immediately in front of the frame cross-member 11 and is journalled on this cross-member. A plurality of actuator shafts 33, usually 6 in number, extend rearwardly from the shaft 30 in perpendicular relationship to this shaft, with their axes substantially in a 15 common plane including the axis of the shaft 30. These actuator shafts are journalled in the frame cross-members 11 and 13. The drive shaft 30 is drivingly connected to the several actuator shafts 33 through individual miter gear drive connections 34 and is itself driven from the 20 machine motor through a suitable cyclic clutch, as is fully disclosed in Patent No. 2,229,889, granted January 28, 1941, to C. M. F. Friden.

Each actuator shaft 33 carries a pair of actuator drums, as indicated at 35 and 36, and each of these drums carries 25 two sets of consecutively stepped gear teeth, as indicated at 40 and 41, for the drum 35. The series of teeth 40 is arranged to impart to a corresponding selection gear from one to five angular increments of one-tenth of a rotation. The series of teeth 41 are arranged 30 to impart to a second gear co-axial with the first gear from six to nine rotational increments of one-tenth of a rotation each.

A keyboard, generally indicated at 42, is securely mounted 35 on the machine to extend forwardly from the frame cross-member 11 and includes a keyboard frame 43 and a plurality of keys having stems 44 slidably mounted for vertical movement in the keyboard frame 43. The keys are arranged in ordinal rows, there being ten rows of keys for a machine having six actuator shafts 33, with the 40 keys in each row numbered from "1" to "9." This constitutes a full keyboard, as disclosed in the Friden Patent No. 2,229,889, referred to above. Selection slides are mounted for longitudinal movement within the machine frame below the keyboard 42. These slides are arranged 45 in ordinal pairs, as indicated at 45 and 46, with each pair disposed below a corresponding ordinal row of keyboard keys. The ordinal selection slides 45 and 46 are provided in their upper edges with notches having differentially inclined faces, as indicated at 50. Each key stem 50 carries near its lower end a perpendicularly projecting pin 51 which engages with the inclined face 50 of the corresponding selection slide notch. The notches in the two slides 45 and 46 of each pair of slides are so arranged 55 that the slide 45 is moved by depression of the "1" to "5" keys of the coordinal row of keyboard keys, and the selection slide 46 is moved by depression of the "6" to "9" keys of the same row. The inclined faces of the notches are so sloped that the slides will be moved a differential amount corresponding to the digit number of the key depressed. The slides are pivotally mounted on the 60 upper ends of supporting links 52, which links are pivotally mounted at their lower ends on the machine frame. Each slide is provided with a rearward extension 53 which extends slidably through a notch 54 in the upper edge of the frame cross-member 11 and over the corresponding actuator drum 35 or 36.

A plurality of square shafts 55 are disposed above, and parallel to, the actuator shafts 33, being journalled in frame cross-members 11, 12 and 15. In the Friden-type 65 calculator having a ten-row keyboard, there will be ten square shafts 55, which square shafts are disposed one at each side of the five lowest order actuator shafts 33.

The sixth actuator shaft does not carry stepped actuating drums 35 and 36 but is provided for the operation of the division mechanism of the machine, which constitutes no part of the present invention.

A pair of selection gears 56 and 57 are slidably mounted on each square shaft 55 against rotation relative to the shaft. The coordinate selection slide 45 is connected to the gear 56 by suitable means, such as the yoke 60 on the rear end of the rear extension of this slide, engaging in an annular groove in the hub of the gear 56, while the slide 46 is connected to the gear 57 by a similar yoke 61, on the rear end of the rear extension 53 of this slide, engaging in an annular groove in the hub of the gear 57.

With this arrangement, the gear 56 is differentially set relative to the series of actuator teeth 40 when any of the "1" to "5" keys of the coordinate row of keyboard keys is depressed, to rotate the square shaft 55 the corresponding number of angular increments. The gear 57 is differentially set relative to the series of actuator teeth 41 when any of the "6" to "9" keys of the coordinate key row is depressed, to rotate the square shaft 55 through the corresponding number of angular increments when the machine is cycled.

A plurality of accumulator dial assemblies, generally indicated at 65, are mounted in ordinal and parallel relationship in the carriage frame 21. Each such assembly includes a dial shaft 66 suitably journaled in the carriage frame 21 and extending perpendicularly to the square shafts 55. Each such dial shaft carries a beveled dial assembly, or accumulator drive gear 67 on its lower end, below the carriage frame 21, and a numbered dial 68 of truncated conical shape on its upper end, above the carriage frame 21. Between the gear 67 and the bottom surface of the carriage frame 21 each shaft 66 carries a tens-transfer cam 70 which cooperates with a tens-transfer bellcrank lever 71 to make a tens-transfer setup in a manner presently to be described. Within the tubular carriage frame 21, each shaft 66 carries a centralizing detent gear 72 and a mutilated resetting gear 73, the latter of which may be actuated by a resetting slide 74 to return the corresponding dial assembly from any differentially set position back to its "0" position in the manner well-known in the art.

Each square shaft 55 carries, below the dial assembly gear 67, an add-subtract gear assembly 75 comprising a cylindrical intermediate, or spool portion, 76 slidably mounted on the corresponding square shaft 55 against rotation relative to the square shaft, and beveled gears 77 and 78 disposed, one at each end of the spool 76 and alternatively engageable with a corresponding dial assembly gear 67, to impart to the dial shaft 66 the same number of rotational increments imparted to the coordinate square shaft 55 by the associated actuator drum 35 or 36. The additive or subtractive position of gear assembly 75 is controlled by an add-subtract gate, generally indicated at 80, which gate comprises a strap 81 disposed below the gear spools 76 and between the gears 77 and 78 and mounted on spaced legs 82. The legs 82 are, in turn, mounted on a transversely extending shaft 83, movement of which is controlled by the add-subtract keys of the machine and by a resilient centralizer device, in the manner well-known in the art. The add-subtract gate is effective to either hold the add-subtract spools in a centered position in which neither gear 77 nor 78 engages the corresponding gear 67 (Fig. 1); or in the add position, in which the gear 77 meshes with the gear 67; or in a subtract position, in which the gear 78 meshes with the corresponding gear 67, this arrangement being fully disclosed in the Friden Patent 2,229,889, referred to above.

When a dial assembly 65 has been turned through angular intervals in either direction from its "0" position, its tens-transfer cam 70 engages the rearward end of the associated tens-transfer lever 71 and rocks this lever about its pivotal connection 88. These levers 71 are so shaped that the depending lug 87 on the transfer lever 71

will engage the forward flange 86 of the transfer gear assembly 85 of the next higher order and shift this gear assembly forwardly to its tens-transfer position. Detenting pins 90 extend between, and are supported at their ends in the frame cross-members 13 and 14, there being a detenting pin for each transfer gear assembly 85. Each detenting pin has thereon a pair of spaced annular flanges 91 which receive therebetween the rearward flange 86 of the associated tens-transfer gear assembly 85. The pins 90 are detained in either the tens-carry or inoperative position of the associated tens-transfer gear assembly 85 to releasably hold the tens-transfer gears in either of these positions. Each of the actuator shafts 33 carries a pair of tens-transfer teeth, as indicated at 92, spaced angularly and longitudinally of the associated shaft 33, one of these teeth being engageable with the tens-transfer gear at one side and the other with the tens-transfer gear at the other side of the corresponding actuator shaft. When a tens-transfer gear has been shifted to its tens-transfer position, as explained above, and the machine is cycled, near the end of the cycle the appropriate tens-transfer tooth 92 will engage a tooth of the shifted tens-transfer gear assembly 85 and impart to such gear assembly a single rotational increment which will rotate the associated square shaft 55 and the corresponding dial shaft 66 through one unit space to advance the corresponding dial 68 one unit space in either the additive or subtractive direction. After the tens-transfer has been completed, as described above, a restore cam 93, mounted on the actuator shaft 33, engages the forward end of the corresponding detenting pin 90 and restores this pin and the tens-transfer gear assembly 85 connected thereto to their rearward, or inoperative, position.

A revolutions counter, generally indicated at 95, is mounted in the carriage forwardly of the accumulator register dial assemblies 65. The counter comprises a plurality of ordinally arranged dial shafts 96, each of which is disposed perpendicular to a corresponding register dial shaft 66 with its rotational axis in a common horizontal plane substantially perpendicular to the plane of the rotational axes of the register dial shafts 66. A numbered dial 97 is mounted on each counter dial shaft 96. Each counter dial shaft carries a mutilated gear 98 engaged by a longitudinally movable clearing rack 99 for clearing the counter register. Each counter dial shaft 96 also carries a shaft rotating gear 100. The counter register mechanism includes an actuator 102 of well-known construction and fully disclosed in the Friden Patent No. 2,229,889 referred to above, which actuator is effective to turn the counter dial assemblies in a manner to register the number of machine cycles occurring during any particular operation of the machine. As this mechanism is all fully disclosed in the above-mentioned Friden Patent No. 2,229,289 and constitutes no portion of the present invention, a more detailed description is considered unnecessary for the purposes of the present disclosure.

The machine carriage is provided with a cover 105, which cover is provided with apertures or window openings, as indicated at 104 and 107, through which the register dials 68 and the counter dials 97 may be viewed by the operator of the machine.

The check dial assembly of the machine, as shown in the Friden et al. Patent No. 2,279,456, is generally indicated at 106 and comprises a housing 107 of rectangular cross-sectional shape, extending transversely across the fixed portion of the machine between the rear end of the keyboard 42 and the front side of the carriage 20 and mounted on the machine frame cross-member 26 and the rear end of the keyboard frame 43. This housing 107 is provided with an arched cover 108, detachably secured to the housing in covering relationship, which housing is provided with apertures or window openings 109 through which the check dials may be viewed by the machine operator.

A check dial shaft 110 extends longitudinally through the housing and is mounted at its ends in supports carried by the housing 107. A plurality of ordinarily arranged check dial assemblies, generally indicated at 115, are mounted on the shaft 110. Each of the check dial assemblies, as particularly illustrated in Figs. 3 and 5, comprises a pair of stepped hubs 116 and 117 coaxially journaled on the shaft 110 in end-to-end relationship to each other, each of which hubs is provided with a nine-tooth gear, as indicated at 118 and 119. A dial 120, having a centrally apertured webbed portion 121, is coaxially mounted on the hub 116 at the side of the gear 118 nearest to gear 119. This dial is provided with an annular flange portion 122 extending from the peripheral edge of the web portion 121 in a direction away from the gear 118 and carrying numerals from "0" to "5," angularly spaced-apart around a portion thereof.

A washer 123 is mounted on the hub 116 between the dial web 121 and an annular flange, or rib, 125 on the inner end of the hub. This washer is drivingly secured to the hub and has a laterally projecting tongue 126 (Fig. 3) received in an aperture in the dial web. A reinforcing washer, or cam, 124 is disposed between the dial flange and the gear 118 so that the dial web is sandwiched between the washers 124 and 123. It is contemplated that the gears 118 and 119 will be formed separately from the hubs and that during the assembly of each unit, the dial and washers will be assembled on the hub against the hub flange 125 and that the corresponding gear will then be pressed onto the hub.

The hub 117 carries a dial 128 secured on the hub between the gear 119 and the inner end of the hub by suitable washers and a flange, as described above in connection with the dial 120. The dial 128 has an annular flange portion 129 which extends from the dial web in a direction away from the gear 119 and surrounds the flange 122 of the dial 120 so that the dials 120 and 128 are nested together. The dial flange 129 carries numerals from "6" to "9," inclusive, and is also provided with a window, or opening, 130 through which the numerals on the dial flange 122 are selectively visible when the dial 128 is in its normal, inactive, position.

A second shaft 135 extends longitudinally of the housing 107 below, and parallel to, the shaft 110 and is mounted at its ends in suitable supports carried by the housing. A plurality of sector assemblies, generally indicated in 136, are rockably mounted on the shaft 135 in spaced relationship, there being one such sector assembly for each dial hub gear 118 or 119. It is understood that, for a ten-bank machine, there will be ten check dial assemblies and that each assembly will have two hub gears. Thus, there will be twenty sector assemblies 136 and each sector assembly will be connected to a corresponding one of the twenty selection slides 45 and 46, in a manner to be presently described.

Each sector assembly 136 comprises an arcuate rack segment 137 having a hub journaled on the shaft 135 and a series of rack teeth 138 meshing with the teeth of the corresponding dial hub gear 118 or 119, and an actuating lever 140, also having a hub journaled on the shaft 135. The actuating lever has a bifurcated arm 141 projecting radially from the hub and having a notch, or opening, receiving a pin 142 projecting laterally from the rearward extension 53 of the corresponding slide 45 or 46.

Each actuating lever also has an arm 143 projecting radially from the hub portion of the lever substantially opposite the arm 141 and disposed between a set screw 144 and a spring 145, both carried by the corresponding sector 137 so that the sector can be angularly adjusted relative to its actuating lever to accurately center the numbers on the dial flanges 122 and 129 in the corresponding window opening 109 of the cover 108.

With the above-described arrangement, when a numeral or digit key of the keyboard is depressed and differentially

moves the corresponding selection slide 45 or 46 in a direction forwardly of the machine, or to the left as is viewed in Fig. 1, the corresponding sector assembly 136 is rocked a predetermined angular amount about its supporting shaft 135 and rotates the corresponding check dial gear 118 or 119 a corresponding angular amount, thereby bringing the proper numeral on the dial flange 129 into registry with the corresponding window opening 109, or the proper numeral on the dial flange 122 into registry with the window opening 130 in the associated dial flange 129 and the cover window opening 109. The check dial mechanism so far described is fully disclosed in the Friden et al. Patent No. 2,279,456 referred to above and provides a means whereby a calculating machine operator can easily read the number which has been entered into the keyboard of the machine to check the accuracy of the entry value before the machine is actuated to use this value in a machine operation, such as an addition, subtraction, multiplication or division operation.

The arrangement, as described above and disclosed in the Patent No. 2,279,456, has been found to operate entirely satisfactorily but has the defect that all of the zeros in the check dial arrangement are visible at all times to the machine operator and this renders somewhat difficult the accurate reading of the entry value shown in the check dials and also the accurate determination of the ordinal position of the entry value, particularly where the entry value contains a relatively small number of digits. The present invention provides means for covering the check dial window openings and control means for uncovering those openings to the right of a selected order of the keyboard; or, in the absence of any such selection, to the right of the highest order digit in an entry value, while leaving the window openings to the left of such selected order or highest order digit closed, so that the zeros to the left of the highest order digit or the selected keyboard order do not show. This mechanism has been hereinbefore referred to as a zero foil, or cover, mechanism and comprises a plurality of ordinarily arranged window covering levers 146; there being one such lever for each check dial assembly 115.

The levers 146 are rockably mounted on a third shaft 147 which extends longitudinally of the housing 107 below the shaft 110 and rearwardly of the shaft 135 and is mounted at its ends on the check dial housing. As is particularly shown in Figs. 2, 4 and 5, each of the levers 146 is a double lever having two legs 149 and 150 disposed in spaced and parallel relationship to each other to provide a U-shaped structure which is rockably mounted at its open end on the shaft 147. The other end of the U-shaped member is closed by an integral intermediate, or bight, portion 152, which, when the lever is in its operative, or zero blanking, position shown in Fig. 1, covers the corresponding check dial window opening 109 in the cover 108. The legs 149 and 150 of each cover lever 146 are disposed at respectively opposite sides of the corresponding check dial assembly, including the dials 120 and 128, and are longitudinally curved to extend forwardly and then upwardly around the forward portions of the check dial hubs. The levers are resiliently urged to their window closing position, as shown in Fig. 1, by individual springs 159 connected between the levers and a spring connecting bar 151 secured between the cover 108 and the rear upper edge of the housing 107. The spacing washers 124 and 154 of each check dial assembly serve also as cams 124 and 154, each of which has a circular lobe portion extending through the major portion of its circumference, and a low portion 155 of limited angular extent. Each of the lever legs 149 and 150 has, intermediate its length, an upwardly extending projection 156, the outer end of which engages the periphery of the corresponding cam 124 or 154. The low portions 155 are so located that when a dial is in its "0" position, the lever projections 156 are in the correspond-

ing low portions 155 and the intermediate, or bight, portion 152, of the lever is in position to cover the corresponding window opening 109. When either of the corresponding dials 120 or 128 is turned away from its full-cycle or "0" position, the notch, or low portion, 155 of the respective cam rotates away from the corresponding projection 156, so that the projection will be engaged by the circular lobe portion 154 of the cam, and this will force the lever down and hold it down in a position in which the corresponding window opening 109 is uncovered.

As is particularly shown in Fig. 5, each cover lever 146 is provided near its upper or free end with laterally directed extensions 157 and 158 extending outwardly and slightly forwardly from the corresponding lever legs 149 and 150, respectively. The extension 157 is reversely bent to include a portion 170 extending perpendicularly to the left from the corresponding lever leg 149 and a portion 171 extending forwardly, substantially perpendicular to the latter portion; while the extension 158 is substantially L-shaped and includes a portion 172 extending to the right from the lever leg 150 from which it projects. It will be noted in Fig. 5 that the right-hand projection 172 of each extension 158 overlies the forwardly extending portion 171 of the projection immediately to the right thereof, which projection is associated with the check dial assembly of the next lower order. Thus, whenever a lever of a check dial assembly above the lowest order is forced downwardly by the turning of the associated check dial to show a digit value, the projection 172 of this lever will engage the projection 171 of the lever to its right and force this lever down to uncover the corresponding check dial window opening, and the second lever will engage and force down the lever to the right of it, etc. Thereby the window opening in registry with a check dial carrying the highest significant digit of an entry value, and all of the window openings to the right thereof, will be simultaneously uncovered.

While the above-described arrangement will provide a construction in which all of the window openings to the right of the highest significant digit of an entry value will be uncovered and all of those to the left of the order carrying such highest significant digit will remain closed, it is, at times, desirable to show a predetermined number of zeros to the left of the highest significant digit in a particular entry value. This is accomplished in the present arrangement by the provision of a decimal setting pointer, as generally indicated at 160.

The decimal pointer assembly 160 comprises a bar 161 extending across the outer surface of the cover 108 immediately in front of the window openings 109 and having its ends secured to the cover and its intermediate portion spaced above the cover, and a manually settable slide 162 mounted on, and slidable along, the bar 161.

The slide 162 has, on the portion thereof adjacent to bar 161, a pointer formation 164, by means of which the operator can accurately determine the setting of the slide relative to the orders of the check dials, and has a portion 165 extending downwardly from the bar 161 through a slot 166 in the cover 108 and provided at its lower end with an arrowhead-shaped formation 167. The formation 167 has opposite edges inclined upwardly and to the left and upwardly and to the right so that when the slide is moved to the left or right along the bar 161 these inclined edges of the slide formation 167 will override the forward extensions 171 of the zero foil levers 146 and force the upper, or free, ends of these levers downwardly to uncover the corresponding window openings 109 in the check dial cover. The bottom end of the formation 167 is flattened, as indicated at 168, so that the lever 171, at the ordinal location at which the slide 162 is stopped, will be held down and all of the zero foil levers to the right of this lever will also be held down because of the overlapping arrangement of the lever extensions 172 and 171, as described above. Thus, all of

the check dial window openings to the right of the position of the zero pointer slide 162 will be held down in position to uncover the corresponding check dial windows 109, and the windows to the left of the position of the slide will remain covered, unless a check dial of an order to the left of that at which the slide is set is turned away from its zero position. In the latter case its zero foil lever will be moved down by the corresponding cam 124 or 154 and any levers between this rotated check dial and the ordinal position of the slide 162 will also be forced downwardly to their window opening position.

With this arrangement, the calculating machine operator can not only determine the accuracy of an entry value, but can also readily determine the ordinal position of the value entered, and whether or not the value contains the proper number of digits properly related to the selected decimal order at which the machine is being operated.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, all changes which come within the meaning and range of equivalency of the claims are, therefore, intended to be embraced therein.

What is claimed is:

1. In a calculating machine having differentially settable selection mechanism including a pair of selection slides in each order settable to different digit positions of the same series of digits, value displaying means including a pair of nested dials in each order mounted for independent rotational movements, means connecting each of said dials to a corresponding selection slide of the same order to move said dials to different angular positions indicating the digit positions of the corresponding selection slides, each of said dials having a series of numbers thereon and the outer of said dials having at one end of the series of numbers thereon an opening through which the numbers on the associated inner dial can be viewed, and a cover covering said dials and having window openings therein through which the numbers on said dials can be viewed, shield means comprising members mounted one adjacent each pair of nested dials for movement into and out of closing relationship to the corresponding window openings in said cover, means resiliently biasing said members to window closing position, means acting between said dials and said members moving said members to window opening position when the corresponding dials are turned away from their "0" position, an ordinarily positionable member operative to move the coordinal shield member from a window closing to a window opening position, and lateral projections on said shield members arranged in overlapping relationship from left to right whereby the movement of any shield member to window opening position moves all shield members to the right thereof to such window opening position.
2. In a calculating machine having differentially settable selection mechanism including a pair of selection slides in each order settable to different digit positions of the same series of digits, value displaying means including a pair of dials in each order mounted for independent rotational movements, means connecting each of said dials to a corresponding selection slide of the same order to move said dials to different angular positions indicating the digit positions of the corresponding selection slides, and a cover overlying said dials and having window openings therein through which said dials can be viewed, shield means for said dials comprising a member rockably mounted adjacent each pair of dials for movement into and out of covering position relative to the corresponding window openings in said cover, means biasing said members to window covering position, means acting be-

tween said dials and said members to move any member to window opening position when either dial of the coordinal pair of dials is turned from its "0" position, a manually positionable means operative to rock a selected shield member from a window closing to a window opening position, and projections extending from said members and overlapping each other in a relationship such that when a member is moved to its window opening position, all of the members to the right of such member will be simultaneously moved to window opening position.

3. In a calculating machine having differentially settable selection mechanism including at least one selection member in each order settable to different digit positions of the same series of digits, value displaying means including at least one dial rotatably mounted in each order, means connecting each dial to a corresponding selection member of the same order to move said dials to angular positions indicating the digit positions of the corresponding selection members, and a cover overlying said dials and provided with window openings through which said dials can be viewed, shield means for said dials comprising members rockably mounted one in each order and adjacent the corresponding dials for movement into and out of position to close the corresponding window openings in said cover, means biasing said members to window closing position, means acting between said dials and said rockable members for moving any member to window opening position when a coordinal dial is turned from its "0" position, overlapping means on said rockable members effective when one member is moved to window opening position to simultaneously move all the rockable members to the right of said one member to window opening position, and a decimal marker slidably along said cover from order to order of said value displaying means and engaging said overlapping means to move the rockable member at the ordinal position of said decimal marker and all rockable members to the right thereof to window opening position.

4. In a calculating machine having selection mechanism including ordinally arranged pairs of endwise movable slides differentially settable to represent different value ranges of the same series of values, value indicating means including ordinally arranged pairs of overlapping indicator elements mounted for independent movement and connected to corresponding slides in the same orders for movement thereby, a cover overlying said indicator elements and having window openings therein, and window closing members movably mounted adjacent said indicator elements and moved to window opening position when the coordinal indicator elements are moved away from their "0" positions, ordinally settable means effective to move the coordinal window closing member away from its window closing position, and means operated by said window closing members for moving all of the window closing members to the right thereof away from their window closing position.

5. A check dial assembly for a calculating machine comprising an elongated housing, a first shaft extending longitudinally of said housing, check dials rotatably

60

mounted in ordinal arrangement on said first shaft, a cover for said housing having ordinally arranged window openings through which said check dials can be viewed, a second shaft extending longitudinally of said housing, means mounted on said second shaft and engaging said check dials to turn the latter to value indicating positions, a third shaft extending longitudinally of said housing, levers mounted in ordinal arrangement on said third shaft and having thereon formations adapted to cover the coordinal window openings in said cover, means urging said levers to position to cover said window openings, cams driven with said dials and engaging said levers to individually move said levers to position to uncover said window openings when the coordinal dials are turned away from their "0" positions, and an ordinally positionable member operative to move the coordinal lever to a position to uncover the coordinal window opening, said levers having projections thereon so arranged that one projection on all except the extreme right-hand lever overlies a projection on the lever immediately to the right thereof so that, when one lever is moved to window uncovering position, all levers to the right of said one lever will be similarly moved.

6. A check dial assembly for a calculating machine comprising an elongated housing, a first shaft extending longitudinally of said housing, check dials rotatably mounted in ordinal arrangement on said first shaft, a cover for said housing having ordinally arranged window openings through which said check dials can be viewed, a second shaft extending longitudinally of said housing, means mounted on said second shaft and engaging said check dials to turn the latter to value indicating positions, a third shaft extending longitudinally of said housing, levers mounted in ordinal arrangement on said third shaft and having thereon formations adapted to cover the coordinal window openings in said cover, means urging said levers to position to cover said window openings, and cams driven with said dials and engaging said levers to individually move said levers to position to uncover said window openings when the coordinal dials are turned away from their "0" positions, said levers having projection thereon so arranged that one projection on all except the extreme right-hand lever overlies a projection on the lever immediately to the right thereof so that, when one lever is moved to window uncovering position, all levers to the right of said one lever will be similarly moved, and a decimal pointer slidably mounted on said cover for movement from order to order along said window openings and engaging the projections on said levers to move the lever at and those to the right of the ordinal position of said decimal pointer to window uncovering position.
